UNITED STATES PATENT OFFICE.

MARTIN B. CRAWFORD AND CHARLES E. TEMPLE, OF TERRE HAUTE, IND.

FAN ATTACHMENT.

SPECIFICATION forming part of Letters Patent No. 272,416, dated February 20, 1883

Application filed December 6, 1882. (No model.)

To all whom it may concern:

Be it known that we, MARTIN B. CRAWFORD and CHARLES E. TEMPLE, of Terre Haute, in the county of Vigo and State of Indiana, have 5 invented certain new and useful Improvements in Fan Attachments; and we do hereby declare that the following is a full, clear, and exact description of the invention, which will enable others skilled in the art to which it appertains 10 to make and use the same, reference being had to the accompanying drawings, which form a part of this specification.

Figure 1 is a perspective view of our improved fly-fan, showing its construction and 15 arrangement for operation. Fig. 2 is a vertical sectional view of the same, and Fig. 3 is a detail view.

The same letters refer to the same parts in all the figures.

20 This invention relates to fly-fans; and it consists in certain improvements in the construction of the same, which will be hereinafter more fully described, and particularly pointed out in the claims.

25 In the drawings hereto annexed, A represents a suitable rod or handle, provided at its lower end with a sleeve, B, having a set-screw, C. D is a rod or stem sliding longitudinally upon the handle A, and having a sleeve, E, 30 encircling the latter, as shown. The stem D may, it will be seen, be moved to any desired position upon the handle A, after which, by tightening the set-screw C, it may be fastened securely in such position. The lower end of 35 the stem D has a cross-piece, F, to which a suitably-constructed brush, G, may be secured by means of a clamping-strip, H, or in any other suitable manner. The handle A is secured at its upper end to a flat spring, I, which 40 is bent, as shown, and secured to the under side of the ceiling of the room in which the device is to be used by means of a clamp, J, (shown in detail in Fig. 3 of the drawings,) and consisting of a plate, K, having a narrow wing 45 or flange turned under it, and provided with a curved bearing-edge for the spring, and with a perforation, M, to receive the fastening-screw N. The plate K, it will be seen, rests against the ceiling of the room, thus preventing the 50 spring from wearing into the same. The curved bearing-edge, which is denoted by letter L, forms a smooth and even bearing for the spring,

the durability of which is thus enhanced, and by the single fastening-screw N the spring and clamp are secured in position. By loosening 55 the screw the spring may be readily lengthened or shortened, as required. The upper end of the handle A has an eye, O, to which is secured a cord or wire, P, leading over suitably-arranged pulleys or screw-eyes Q in one of the 60 walls of the room, and having its other end attached to a foot plate or stirrup, S, secured to the lower end of a rod, R, having at its upper end a hook, T, by which it may be hooked or suspended in a staple, U, under a table or 65 similar piece of furniture in the room.

The operation of our invention will be easily understood from the foregoing description, taken in connection with the drawings hereto annexed. A person seated at the table, which 70 in the drawings is denoted by V, may with great ease operate the swinging rod T, thus, through the medium of the cord or wire P, operating the brush or fan, which is retracted by the spring I, and which, being suspended by 75 the said spring, has a shaking or vibrating motion, which is very desirable and useful in this class of devices. The elevation of the brush over the table may be readily adjusted by raising or lowering the stem D. 80

When the device is not in use the brush may be raised to its limit, so as to be out of the way, and the swinging rod may be detached from the table and suspended upon a hook, W, upon the wall by means of a ring or eye, X, 85 secured to the cord P near the stirrup S. When the rod R is thus suspended the cord or wire P is stretched and the brush drawn up to the position shown in dotted lines in Fig. 2, thus lifting it out of the way of persons moving 90 about in the room.

In lieu of the cord and pulleys herein shown, rods and bell-crank levers may be employed for communicating motion from the swinging rod R to the brush. It may also be found expedient to supplement the spring I with a coiled spring, Y, connecting the upper end of the brush-handle with a hook, Z, under the ceiling; or the said coiled spring may take the place of the spring I, in which case the brush-handle should be hinged directly under the 100 ceiling.

We claim as our invention and desire to secure by Letters Patent of the United States—

1. The herein-described fly fan or brush, consisting of a handle suspended under the ceiling by means of a flat spring, and having a sleeve provided with a set-screw to retain an extension-handle, having at its upper end a sleeve encircling the handle and at its lower end a cross-bar carrying the brush, in combination with suitable mechanism for reciprocating or vibrating the said fan or brush, as set forth.
2. The combination, with the herein-described fly fan or brush having a flat spring at its upper end, of the clamp or plate K, having under-turned wing or flange provided with a curved bearing-edge, L, and perforation M, and the set-screw N, as and for the purpose set forth.
3. The combination of the fly-fan, the suspending-spring, the swinging rod R, having stirrup S, a cord or wire connecting said stirrup with the said fly-fan, and suitable guide pulleys or eyes, as and for the purpose set forth.
4. The combination of the fly-fan, the suspending-spring, the detachable swinging rod R, having stirrup S, the cord P, connecting said stirrup with the fly-fan, and having ring X, suitable guide pulleys or eyes, and the hook W, all arranged and operating substantially as set forth.

In testimony that we claim the foregoing as our own we have hereto affixed our signatures in presence of two witnesses.

MARTIN B. CRAWFORD,
CHARLES E. TEMPLE.
